Primary Examiner — Adir Aronovich*Assistant Examiner* — Ramzi Almatrahi(74) *Attorney, Agent, or Firm* — Knobbe, Martens, Olson & Bear LLP(57) **CLAIM**

The ornamental design for a camera, as shown and described.

DESCRIPTION

This application relates to U.S. application Ser. No. 29/514, 594, filed Jan. 14, 2015, entitled “camera,” and to U.S. application Ser. Nos. 29/500,105, 29/500,109, 29/500,113, 29/500,116, and 29/500,126, all filed Aug. 21, 2014 and all entitled “camera.”

FIG. 1 is a perspective view of a camera showing the new design;
FIG. 2 is a front view thereof;
FIG. 3 is a back view thereof;

FIG. 4 is a left side view thereof;

FIG. 5 is right side view thereof;

FIG. 6 is a top view thereof; and,

FIG. 7 is a bottom view thereof.

The broken lines depict portions of a camera in which the design is embodied and form no part of the claimed design.
